CHANUKAH TABLE PLACE MAT

Sara Rae Naimon, Milwaukee, Wis.

Application March 12, 1956, Serial No. 40,565

Term of patent 14 years

(Cl. D92—26)

Fig. 1.

Fig. 2.

I claim:

The ornamental design for a Chanukah table place mat, as shown.
